JESSE E. WILHELM, OF CLEVELAND, OHIO, ASSIGNOR TO THE GREAT LAKES DREDGE & DOCK COMPANY, OF CHICAGO, ILLINOIS, A CORPORATION OF NEW JERSEY.

FORM FOR CASTING REINFORCED-CONCRETE PILES.

1,285,864.

Specification of Letters Patent. Patented Nov. 26, 1918.

Original application filed November 3, 1915; Serial No. 59,386. Divided and this application filed March 30, 1916. Serial No. 87,754.

To all whom it may concern:

Be it known that I, JESSE E. WILHELM, a citizen of the United States, residing at Cleveland, in the county of Cuyahoga and 5 State of Ohio, have invented a certain new and useful Improvement in Forms for Casting Reinforced-Concrete Piles, of which the following is a full, clear, and exact description, reference being had to the accompanying 10 drawings.

This invention relates to concrete piles having laterally extending interlocking devices. Such a pile is shown, described and claimed in my prior application, Serial No. 15 59,386, filed November 3, 1915, and of which this application is a division. The general object of the invention is to provide a simple efficient and comparatively inexpensive 20 mold in which the pile may be cast, providing for the most convenient assembling of a pile with the interlocking members.

The pile produced by my process comprises a concrete body cast about a suitable reinforcing skeleton, and preferably having 25 a longitudinal opening along the axis of the pile. The interlocking device preferably comprises laterally projecting metal wings, each adapted to coact with a corresponding member on the next adjacent 30 pile, these wings seating in longitudinal grooves in the body of the pile and being secured in position by members extending transversely around the exterior of the pile. These latter members are preferably carried 35 in grooves so that they may not interfere with driving the pile.

In carrying out my invention the pile is cast in a mold comprising two or more longitudinal separable sections having trans- 40 verse inwardly extending ribs or projections adapted to form transverse grooves around the perimeter of the pile. These grooves are preferably spaced apart and extend substantially half way around the pile, and 45 those extending in one direction are offset or intermediately positioned with relation to those extending in the other direction. These transverse grooves meet oppositely positioned grooves extending preferably 50 throughout the length of the pile and which are formed when the pile is cast. The interlocking members have one edge adapted

to coact with an interlocking device on the adjacent pile and have the other edge adapted to seat in the longitudinal grooves and 55 are preferably provided with a series of openings registering with the transverse grooves. Rods lying in these grooves have their ends projecting through the openings in the interlocking members and nuts on 60 the ends of these rods may act to effectively hold the interlocking members in place.

The longitudinal opening along the axis of the pile may be formed by a tubular casing or pipe firmly cast into the pile and 65 forming part of the same, or this opening may be formed by a collapsible core which is withdrawn after the concrete forming the pile is set. In either instance the core or the tubular member is positioned with relation to the pile by suitable ties extending around the core or pipe and secured to various longitudinal rods forming part of the 70 reinforcing structure which is positioned in the mold as is hereinafter described. A 75 suitable driving point may be provided at the lower end of the pile.

The mold is provided with inwardly extending ribs corresponding to the longitudinal and transverse ribs of the pile assembled about a reinforcing skeleton; one end of the mold is closed by a suitable driving point for the pile; the concrete is then poured into the mold; after the concrete is set the mold is removed; the interlocking 80 members are seated in the longitudinal 85 grooves; and the transverse securing members are then placed in position in the grooves with their ends engaging the interlocking members and are suitably secured 90 thereto. The pile is preferably provided with a longitudinal passage extending axially throughout the length of the pile, and this passage may be formed either by casting a suitable tube into the pile which 95 may form a part of the same when the concrete is set, or may be formed by a collapsible core adapted to be removed after the concrete is set. The longitudinal passage thus formed provides for conveniently 100 anchoring the pile to rock or other hard strata, through which the pile cannot be driven. The anchoring may be accomplished by drilling several feet into the rock

after the pile is in position by operating a drill through the longitudinal opening and then dropping through this opening to the lower end of the pile a suitable post or 5 anchor member adapted to extend into the rock and upwardly into the pile. This opening may also be used for jetting the pile by forcing water downwardly through the same.

10 The drawings illustrate one form of pile which may be constructed by my forming devices and also show the collapsible core which may be used in its construction. I will now describe my invention particularly 15 with reference to such drawings.

Figure 1 is a side elevation of two piles, showing the interlocking and anchoring features; Fig. 2 is a plan of one of the piles showing the interlocking members secured 20 in position; Fig. 3 is a horizontal section showing a portion of the reinforcing means and the means for holding the core, for the longitudinal passage, in position; Fig. 4 is a transverse section through a mold showing 25 the reinforcing structure and axial core in position ready for casting the pile; Fig. 5 is a longitudinal sectional detail of the mold shown in Fig. 4 taken on a smaller scale; Fig. 6 is a longitudinal sectional detail 30 showing the members for forming the longitudinal and transverse grooves of the pile, the section being taken along a joint of the mold; Fig. 7 is a detail of one of the transverse members for securing the interlocking 35 devices in position; Fig. 8 is a somewhat diagrammatic view showing the method of forming the axial opening through the pile by means of a collapsible core; Fig. 9 is an end elevation of such collapsible core; and 40 Fig. 10 is a perspective of the member for forming the longitudinal groove and the recesses at each side thereof.

Referring to the drawings by numerals, the concrete pile 1 is preferably of an octagonal form made conical-shaped at its 45 lower end, as indicated at 2, and provided with a metal cap 3 secured to the concrete and adapted to prevent the crushing of the point of the pile while it is being driven.

50 The interior of my concrete pile is preferably reinforced by a steel structure similar to the usual construction. As shown, this reinforcing skeleton comprises a plurality of spaced apart longitudinal rods 5 preferably 55 extending substantially throughout the length of the pile. These rods are relatively positioned and spaced with relation to each other by encircling rods 6, which are shown as looping around each of the vertical rods 60 5. These encircling rods may be provided in any desired number and arranged at separated points throughout the length of the pile.

65 The form of the interlocking feature of the pile shown in the drawings will now be

described. In casting the pile the concrete is formed with diagonally opposite grooves 10 shown at corners of the octagonal surface and extending throughout the length of the pile. Grooves 12 extend transversely around the outside of the pile from one groove 10 to the other and these grooves 12 are suitably spaced apart and extend in alternately opposite directions about the pile. Opposite the points where the ends of the grooves 12 meet the grooves 10, are provided recesses 13 as shown in Figs. 2 and 3. These longitudinal and transverse grooves receive the metal wings and the means for holding them in position whereby one pile may be 80 interlocked with and braced by the next adjacent pile to form a substantially tight wall having great durability and strength.

At 15 are indicated interlocking members having one edge adapted to seat in the longitudinal grooves 12, the opposite edge being provided with a recess 16 and a tongue portion 17 adapted to fit in the corresponding recess of the interlocking member on the next adjacent pile, after the manner of the usual form of interlocking steel sheeting. 85 These interlocking members are provided with a series of openings which may stand opposite the ends of the grooves 12 when in position and receive the threaded ends of 90 securing rods 20. The ends of these securing members 20 are adapted to receive nuts 21 which occupy the recesses 13 and it may be tightened to clamp the interlocking members securely in position.

100 It will be seen that with a series of the members 20 extending alternately in opposite directions around the exterior of the pile and through the interlocking members, the nuts 21 being tightened in position, that the interlocking members will be very rigidly and permanently secured to the pile. The securing members 20 are preferably round rods bent to fit the grooves 12 and lie entirely within the same, and it should be 110 noted that when in position they do not interfere with the driving of the pile. These securing members not only serve to hold the interlocking members against longitudinal or lateral displacement, but they materially 115 add to the strength of the pile.

When the interlocking members are assembled on the body of the pile, as described, the piles may be driven side by side with the interlocking members in engagement. The 120 permanency of the concrete, strengthened by the interlocking members, not only provides a strong rigid wall, but the interlocking devices so connect the piles that the wall is substantially water-tight. Whenever it is 125 desirable, the lower ends of the pile may be anchored to rock or other hard strata indicated at 25 in Fig. 1, by drilling downwardly into the rock through the longitudinal passage 26 and then dropping through 130

this opening a suitable post 27 adapted to substantially fit the drilled hole in the rock and extend upwardly into the longitudinal passage, thereby serving to prevent lateral displacement of the lower end of the pile.

Heretofore the interlocking members have been provided on piles of this character by securing them to members of the reinforcing skeleton and then surrounding the skeleton 10 ton and the interlocking members with a mold or casting. Great difficulties are encountered in securing such reinforcing members to the skeleton and the handling is made awkward. The greatest 15 difficulty, however, is in making a mold which will fit the exterior of the reinforcing members close enough to prevent leakage of the concrete and still permit the mold members to be conveniently placed in position 20 and readily removed. The reason for this latter difficulty is that the reinforcing skeletons become bent and warped from stacking them after being built, the distance between the interlocking wings is altered, and they 25 no longer fit the portion of the mold designed to be complementary thereto.

In casting my pile I prefer to use an octagonal mold divided at diametrically opposite points thereby comprising two half mold 30 members 30 and 31 adapted to be secured together by suitable angle bars as indicated at 32 in Fig. 4. These angle bars may be secured together for casting by readily removable bolts, clamps or other devices. At one 35 end of the mold may be provided any suitable means (not shown) for holding the cap 3 in position during the casting of the pile. The grooves 12 are formed by inwardly extending transverse ribs 36 carried by the 40 mold. Portions 38, in the nature of enlargements of the ribs 36, at their opposite ends are adapted to stand against and be rigid with inwardly projecting longitudinal ribs 40 which form the longitudinal grooves 10 in 45 the pile. The detail in Fig. 6 indicates the shape of the ribs 36 which extend through notches in the longitudinal ribs 40 and abut the members 38. The longitudinal ribs 40 are preferably positioned by the mold members 50 and 31 being held against shifting by the ribs 36 extending into the notches 39 (Fig. 10) and abutting the members 38. These members or heads 38 stand alternately on opposite sides of the ribs 40 and form the 55 cavities 13 in the proper positions in the pile. After casting the pile, the mold members 30 and 31 are first removed, leaving the ribs 40 free to be withdrawn radially carrying with them the members 38.

60 The sectional view in Fig. 4 shows the reinforcing structure and core in position in the mold. The core is shown as held in place by tie rods 42 which preferably loop at their ends around diametrically opposite rods 5. 65 One of these tie rods 42 preferably extends

around one side of the core and then several feet along the mold another tie member 42 extends around the opposite side of the mold and is attached to the same vertical rods 5. Still farther along other of these tie members similarly arranged, may extend from others of the vertical rods 5, thus positioning the core while leaving as much open space as possible to permit the free flowing of concrete into the mold.

70 The reinforcing skeleton may be positioned in the mold in any suitable manner. As a convenient means I have shown loops 44 which may be formed at the end of some of the tie rods 42, and project outwardly 80 past the rods 5 engaged thereby, and extend into and engage corners of the mold as shown. Thus, the reinforcing skeleton for the pile and the collapsible core or tube for forming the longitudinal passage are centrally positioned while the concrete is 85 poured into the mold.

A convenient form of collapsible core for the longitudinal opening of the pile is illustrated in Figs. 8 and 9 and is shown as comprising three members 50, 51 and 52 adapted to extend throughout the length of the pile and constructed to nest together as indicated in Fig. 9, to form a substantially cylindrical core. It will be noted that each of the members comprising the core has a peripheral area of less than half of the circumference of the core and the member 50 has two surfaces 53 and 54 which taper toward the center as they approach one end of the pile.

90 In operation, the core is nested in its proper form within the reinforcing structure and its lower end is positioned against a suitable cap point or plug 57 adapted to close the lower end of the cap member 3. The pile 100 body is then cast about the core within the mold, and after the concrete has hardened or set, the separate members of the core may be withdrawn longitudinally. At 58 are indicated suitable eyes by which a suitable 105 pulling device may be attached to these several members. The member 50 is first withdrawn longitudinally upwardly as shown in Fig. 8, and it will be noted that upon first upward movement this member will become 110 loosened and withdrawn freely. The member 51 will then be free and may be withdrawn, and the member 52 then resting entirely loosely in the passage may follow. To facilitate withdrawing the first member, the 115 entire core is preferably tapered slightly so that the upper end is larger in diameter than the lower end, as it will be seen from Fig. 9, the lower end being indicated by the broken line 59.

120 It will be seen from the foregoing description that it is desirable to have the interlocking members independent of the reinforcing structure. For convenience in the 125 operation of the mold in casting the pile, 130

as well as for the purpose of providing a pile which may be used either as an interlocking pile or as an ordinary pile, or may be equipped with interlocking members. In the 5 apparatus I have provided for making such piles, the mold parts for the exterior are simple and easily handled, as they comprise two parts separable on the same plane.

Having thus described my invention, what 10 I claim is:

1. A mold for casting concrete piles comprising longitudinally separable members, means for securing the same together, longitudinally extending inwardly projecting ribs 15 adapted to form grooves in the outer surface of the pile and positioned by but separable from the mold members, and transversely extending inwardly projecting ribs carried by the mold arranged to extend

around the inner surface of the mold from 20 one longitudinal rib to another.

2. A mold for casting concrete piles comprising a plurality of longitudinally separable members, means for securing them together, inwardly projecting ribs positioned 25 at the joints of the mold and extending longitudinally along the same for substantially the full length of the pile to be cast, inwardly projecting ribs on the inner surface 30 of the mold extending in alternate directions from one longitudinal rib to another and secured to the inner surface of the mold, and means for forming recesses in the pile opposite the point where the transverse ribs meet the longitudinal ribs.

In testimony whereof I hereunto affix my signature.

JESSE E. WILHELM.
